PORTABLE PICTURE SCREEN

Laurel E. Cooley, Sr., and Laurel E. Cooley, Jr., La Grange, and Carl O. Plaul, Chicago, Ill.

Application May 25, 1956, Serial No. 41,658

Term of patent 14 years

(Cl. D61—1)

Fig. 1 is a side elevational view of a portable picture screen, showing our new design.

Fig. 2 is a cross sectional view taken on the line 2—2 of Fig. 1.

Fig. 3 is a top plan of the end cap for the screen casing and the end cap for the screen slat of Fig. 1.

Fig. 4 is a cross sectional view taken on the line 4—4 of Fig. 3.

The dominant features of our new design are shown in solid lines in the drawing.

We claim:

The ornamental design for a portable picture screen, as shown and described.
